[57] CLAIM

The ornamental design for a toothpick, substantially as
shown and described.

DESCRIPTION

FIG. 1 is a side elevational view of a toothpick showing
my new design, with the opposite side elevational view
being a mirror image thereof;

FIG. 2 is a top plan view thereof;

FIG. 3 is a bottom plan view thereof;

FIG. 4 is a right hand end view thereof;

FIG. 5 is a left hand end view thereof; and

FIG. 6 is a perspective view thereof, looking down
upon the interior of the pick from the upper right.

FIG. 2

FIG. 5

FIG. 1

FIG. 4

FIG. 3

FIG. 6
